UNITED STATES PATENT OFFICE.

JOSEPH B. SCHAEFFER, OF PINE FORGE, PENNSYLVANIA.

EGG-TESTER.

1,218,481.

Specification of Letters Patent. Patented Mar. 6, 1917.

Application filed August 18, 1915. Serial No. 46,117.

To all whom it may concern:

Be it known that I, JOSEPH B. SCHAEFFER, a citizen of the United States, residing at Pine Forge, in the county of Berks, State of Pennsylvania, have invented certain new and useful Improvements in Egg-Testers; and I do hereby declare the following to be a full, clear, and exact description of the invention, such as will enable others skilled 10 in the art to which it appertains to make and use the same.

This invention relates to new and useful improvements in egg-testers.

An object of the invention resides in the 15 provision of a device by means of which the fertility of an egg may be ascertained.

A further object of the invention resides in the provision of a device which will be inexpensive to manufacture and simple to 20 operate.

With these and other objects in view, such as will appear as my description progresses, my invention comprises the combination and arrangement of parts as set 25 forth in and falling within the scope of the appended claim.

In the drawing:

Figure 1 is a longitudinal sectional view 30 of my device;

Fig. 2 is a bottom plan view;

Fig. 3 is a view looking in the large end 35 of the device; and

Fig. 4 is a similar view looking at the opposite end.

Referring to the drawing by reference 40 characters wherein like parts are indicated by like characters throughout the several views:

In the embodiment of the invention 45 shown in the drawing, I have illustrated a casing 1 which is made of any suitable light and flexible material. This casing is tapered from one end to the other and is open at both ends, the contour of the end 2 being such that the device may be readily fitted to the face of the user. The casing 1 is provided with an opening 3 at the bot-

tom thereof. Located in the small end of the casing 1 is a wall 4 which is provided with an opening 5 adjacent the opening 3 50 in the casing 1. Extending upwardly from this wall 4 is a deflector plate 6 which is arcuate in cross section and which is so arranged that the rays of light will be reflected through the opening 5. 55

In using the device the small end is placed near a light and the large end of the casing is placed to the face of the user. The light will be visible through the opening 5 in the wall 4. The egg is inserted into 60 the casing through the opening 3 therein. The presence of the light behind the egg will render the egg translucent so that the user may see through the same to determine whether or not it is fertile. 65

It will thus be seen that I have provided a very simple device for testing the fertility of eggs.

While I have illustrated and described a particular embodiment of my invention, it 70 has merely been for the sake of convenience and I do not wish to be limited to that particular embodiment as it is obvious that numerous changes may be made in the details of construction without departing from 75 the spirit of the invention or exceeding the scope of the appended claim.

What I claim is:

An egg tester comprising a substantially frusto-conical casing having its ends open 80 and an opening in the bottom adjacent the smaller end thereof, a transverse wall in the small end of the casing having an opening at the bottom thereof, and a deflector plate extending in an inclined direction 85 from said wall and the edge of the opening therein to the adjacent end of said casing.

In testimony whereof, I affix my signature, in the presence of two witnesses.

JOSEPH B. SCHAEFFER.
